UNITED STATES PATENT OFFICE.

JOHN NEWSOME, OF HOLYOKE, MASSACHUSETTS.

SPINNING-MACHINE.

SPECIFICATION forming part of Letters Patent No. 780,300, dated January 17, 1905.

Application filed February 29, 1904. Serial No. 195,740.

To all whom it may concern:

Be it known that I, JOHN NEWSOME, a subject of the King of Great Britain, and a resident of Holyoke, in the county of Hampden and State of Massachusetts, have invented certain new and useful Improvements in Spinning-Machines, of which the following is a full, clear, and exact description.

This invention relates to improved means for driving the spindles of spinning-machines, the object being to obviate the use of the common textile spindle-driving bands which run around a main drum and the individual whirls of the spindles and which, as well-known, not only become stretched and of uncertain tension, but too frequently break, rendering the machine temporarily inoperative.

The object of this invention is to make use of friction-disks one series of which are carried by the spindles, while the other series thereof are carried on a common shaft to which rotation is imparted, the latter disks being in frictional contact with those of the spindles; and it is the object of the invention to acquire an arrangement of the disks whereby, without any especially nice construction and adjustment, the frictional bearing for the driving may be constantly uniform for all of the spindles.

Another object of the invention is to render the driving arrangements susceptible easily of reversal; and a still further object is to so construct, arrange, and combine the parts that the whole driving apparatus is of extreme simplicity and comprises but a minimum of essential components.

The invention consists in the combination and arrangements of parts and the construction of certain of the parts, all substantially as hereinafter described, and set forth in the claims.

In the drawings, Figure 1 is an end elevation, with parts in section, of the carriage portion of a mule, showing the improved spindle-driving mechanism. Fig. 2 is an elevation of the same as seen at the left at right angles thereto. Fig. 3 is a view in detail showing the driving-shaft carrying a plurality of friction-disks and in section showing the

manner of engagement of the disks of the shaft.

Similar characters of reference indicate corresponding parts in all of the views.

In the drawings, A represents the carriage of a mule, provided on which are upper and lower rails B and C, the upper rail having a series of journal-openings *a* therein, through which are journaled the lower portions of the spindles D for carrying the bobbins, these spindles being made without whirls and have near their lower ends each a friction-disk E affixed thereto, each of which disks, as shown, being of frusto-conical form downwardly tapering, and below the lower end of each of these disks E is a step end or journal projection F, which has bearing for rotation in an upwardly-opening socket *b* in the upper part of a curved bracket G, the reversely-turned member *d* of which is screwed or otherwise secured to the lower rail C.

J represents a shaft supported for rotation in suitable journals horizontally and in suitable proximity and right-angular relation to the lengths of the spindles D. As indicated at *f*, some of the brackets may have ears with horizontal circular journal-holes therethrough, in and through which the shaft J receives support, said shaft being, furthermore, supported through bearings in the ends of the carriage or spinning-frame. The shaft J has a grooved collar *g* at its end, coöperating with which is a shipper-lever *h*, whereby the shaft may through this lever have a degree of endwise movement imparted thereto. The shaft is rotated in any suitable manner, as through the gearing indicated at *m*, the primary actuating means for which may be of any character desired.

M M represent a series of friction-disks which are mounted to rotate in unison with the shaft J, and their arrangement is such that one of each has a bearing frictionally against the periphery of a respectively adjacent spindle-disk E. These disks M, as shown, are in the form of double frusto-conical members, the taper of each side, corresponding to the taper of the spindle-disks. While, as understood from an inspection of Fig. 2, the series

2

of disks M may be adjusted and affixed with a nicety on the shaft J, so that all of the disks will simultaneously be in frictional contact against the spindle-disks, provisions as represented in Fig. 3 are practical and very desirable, the same including a spline-groove n in the shaft J, in which a spline o for each disk M engages, and a spiral spring q, applied between an abutment or shoulder t on the shaft and the side of the disk. By endwise shifting the shaft J through the shipper-lever described the disks M may have their bearings either at the right-hand sides of the spindle-disks or relatively at the left-hand sides of such disks to correspondingly drive the spindles in either direction desired, and when the shaft J is, for instance, moved leftward to bring the shaft-carrier disks M to work at the right-hand sides of the spindle-disks the collars or abutments t on the shaft will crowd the spiral springs relatively at the right-hand sides of the disks M to exert a pressure in a leftward direction against such disks, so that they will be under a yielding spring stress, the degree of which for proper frictional driving may be determined by the constructor in the selection of a spring of appropriate potentiality, and of course as those springs to the rightward of the disks M are brought into abnormal compression those at the left of such disks react and are of lessened stress or are usually under no tension.

While the spindle-driving devices are here illustrated as applied in conjunction with a part of a mule, they are as well applicable on any of the other well-known kinds of spinning-machines, and it is almost needless to say that the described devices will run for an extremely long period without the necessity of replacement and during the use thereof the annoyance of stopping for regulating the tension or for the replacement of spindle-driving bands is obviated.

Having thus described my invention, what I claim, and desire to secure by Letters Patent, is—

1. For a spinning-machine, the combination with a series of rotatable spindles having frusto-conical disks affixed thereon, of a shaft mounted for rotation and for axial movement, and having a series of double frusto-conical friction-disks, endwise movable, but non-rotatable relatively to said shaft, and springs normally in compression and reacting against the sides of said shaft-carried disks and means for imparting axial movements to said shaft and the disks yieldingly mounted thereon.

2. In a spinning-machine, the combination with a rail and a series of rotating spindles extending therethrough and provided below

the rail with a series of friction-disks, and having journal projections therebelow, of a series of brackets having step-sockets in their upper portions receiving said projections, a shaft arranged right angularly to the lengths of the spindles, and having a series of friction-disks engaging the spindle-disks and means for rotating said shaft.

3. In a spinning-machine, the combination with the upper and lower rails, and a series of rotating spindles extending through the upper rail and provided therebelow with a series of friction-disks, and having journal step projections at their extremities below the disks, of a series of brackets supported on the lower rail and having step-sockets in their upper portions receiving therein the spindle journal-steps, a shaft arranged right angularly to the lengths of the spindles, and having thereon a series of friction-disks engaging the spindle-disks, and means for rotating said shaft.

4. In a spinning-machine, the combination with the upper and lower rails, and a series of rotating spindles extending through the upper rail and provided therebelow with a series of friction-disks, and having journal step projections at their extremities below the disks, of a series of brackets supported on the lower rail and having step-sockets in their upper portions receiving therein the spindle journal-steps, a shaft and several of said brackets having horizontally-alined journal-openings therethrough, a shaft, having bearing-supports through said alined openings in said brackets, arranged right angularly to the lengths of the spindles, and having thereon a series of friction-disks engaging the spindle-disks, and means for rotating said shaft.

5. In a spinning-machine, the combination with a series of rotatable spindles having disks affixed respectively thereon, of a shaft arranged right angularly to the lengths of the spindles, and having a series of double-faced friction-disks mounted thereon for rotation in unison therewith but capable of individual movements, along the lengths of said shaft, abutments appurtenant to said shafts and at opposite sides of the respective disks thereon, spiral springs encircling the shaft and arranged between the abutments and the opposite sides of the disks, means for rotating, and means for endwise shifting, said shaft.

Signed by me at Springfield, Massachusetts, in presence of two subscribing witnesses.

JOHN NEWSOME.
